(57) CLAIM

The ornamental design for a diaper with removable pouches, as shown and described.

DESCRIPTION

FIG. 1 is a front elevation view of a diaper with removable pouches showing my new design;

FIG. 2 is a rear elevation view thereof;

FIG. 3 is a right side elevation view thereof, the opposite side being a mirror image of the shown;

FIG. 4 is a top plan view thereof;

FIG. 5 is a bottom plan view thereof; and,

FIG. 6 is an exploded isometric view thereof.

The broken lines shown in FIGS. 1 and 6 depict wording as environmental subject matter only and form no part of the claimed design. The remaining broken lines shown in FIGS. 1 and 6 illustrate portions of the diaper with removable pouches that form no part of the claimed design.
